UNITED STATES PATENT OFFICE

136,525

DESIGN FOR A HAT

Zinaida Harpignies, Kew Gardens, N. Y.

Application April 3, 1943, Serial No. 109,901

Term of patent 7 years

To all whom it may concern:

Be it known that I, Zinaida Harpignies, a citizen of Belgium, residing at 84-09 Talbot Street, Kew Gardens, L. I., in the county of Queens and State of New York, have invented a new, original, and ornamental Design for a Hat, of which the following is a specification, reference being had to the accompanying drawing, forming part thereof.

In the drawing

Fig. 1 is a top plan view of a hat showing my new design;

Fig. 2 is a side elevational view of the hat shown in Fig. 1;

Fig. 3 is a front perspective view thereof, and Fig. 4 is a rear perspective view thereof.

I claim:

The ornamental design for a hat, as shown.

ZINAIDA HARPIGNIES.
